UNITED STATES PATENT OFFICE

MARCEL M. MICHELIN, OF STATEN ISLAND, NEW YORK, ASSIGNOR TO PINAUD INCORPORATED, OF NEW YORK, N. Y., A CORPORATION OF NEW YORK

DESIGN FOR A DISPLAY CARD OR SIMILAR ARTICLE

Application filed October 29, 1929. Serial No. 33,207. Term of patent 14 years.

To all whom it may concern:

Be it known that I, MARCEL M. MICHELIN, a citizen of the Republic of France, a resident of Staten Island, Richmond County, New York State, have invented a new, original, and ornamental Design for a Display Card or Similar Article, of which the following is a specification, reference being had to the accompanying drawing, forming a part thereof.

Fig. 1 is a top plan view; and
Fig. 2 is an elevation.

I claim:

The ornamental design for a display card or similar article as shown.

MARCEL M. MICHELIN.
